MATRIX TRANSFER

David Diamond, Brooklyn, N. Y.

Application October 8, 1937, Serial No. 168,036

19 Claims. (Cl. 199—36)

The purpose of this invention is to provide improvements in the construction of Linotype or other similar machines for handling matrices between the transfer slide and distributor without using the teeth of the matrices as the holding means.

The invention relates to improvements in the construction of parts of Linotype or other similar machines, and particularly the transfer channel second elevator, elevator transfer slide and space band lever pawl, in which the matrices are separated from the space bars and raised vertically to the second elevator, in that they are gripped and held by the side lugs at their upper ends, and, as the second elevator is moved upward, the matrices are gripped and held therein, and the space bars are returned by the return movement of the transfer slide as at present.

This invention is an improvement over a similar device as described in my copending application with the Serial Number 155,892, filed July 27, 1937, in that substantially all of the operating parts are located on the same side or back of the transfer channel, the matrices are gripped on both sides instead of one, and also in that the respective movements of the operating parts have been simplified, and, at the same time, made absolutely positive.

In Linotype and other similar machines the matrix, from which the type face is formed, is formed with a V shaped groove in the upper end, with notches in the edges thereof forming sorting teeth, and these teeth are used to support the matrix as it is elevated from the transfer channel by the second elevator to the sorting mechanism, and in transferring the matrix from one part to another the sorting teeth are damaged, which results in the matrix being placed in the wrong position by the sorting mechanism, and the teeth are often damaged to such an extent that the matrix is discarded. The life of the matrix is, therefore, dependent upon the damage to the sorting teeth thereof.

The object of this invention is, therefore, to eliminate the chance of damage to these teeth, particularly by the use of the teeth in conveying the matrix from one position to another, and more specifically in the use of the teeth in the second elevator.

Another object is to provide means for supporting the matrix in the second elevator without using the sorting teeth.

Another object is to provide means for transferring the matrix from the transfer channel to

the second elevator without using the sorting teeth.

Another object is to provide means for transferring the matrix and delivering it to the second elevator, in which the matrix may be raised without raising the space bar.

Another object is to provide holding means in the second elevator in a Linotype or similar machine for the matrix, which supports the matrix from the under side of the lugs at the sides of the upper end thereof.

Another object is to provide means for supporting the matrix before it is delivered to the second elevator from the lower end thereof.

Another object is to provide means for operating a movable stop for engaging matrices in the transfer channel which moves with the line, and which is automatically returned to the starting position.

Another object is to provide a resiliently held bar in the transfer channel of Linotype machines for resiliently engaging the sides of matrices and the like which readily holds the said matrices in a fixed position.

Another object is to provide movable means for sliding in under the shoulders at the upper ends of matrices, and means operating said movable means, withdrawing the same to permit entrances of the matrices, and releasing the same to grip and hold the matrices after they are in place.

Another object is to provide means for transferring matrices from the transfer channel to the second elevator, in which the matrices may be fed to the intermediate channel at different elevations, thereby eliminating the means for lining up the matrices when two sets of dies thereon are used.

A further object is to provide means for delivering the matrix of a Linotype or other similar machine to the second elevator by a vertical movement.

And a still further object is to provide means for transferring and supporting the matrix of a Linotype or other machine to and in the second elevator without using the sorting teeth, which is of a simple and economical construction.

With these ends in view the invention embodies mechanism for supporting the matrix of a Linotype or other similar machine from the lower end, means for supporting the space bars, means for elevating the matrix without moving the space bar, means for gripping and holding the matrix by the second elevator without engaging the sorting teeth of the matrix, means for oper-

ating the said holding means, and means for raising one end of the space band lever pawl as the said pawl approaches the end of the second elevator.

5 Other features and advantages of the invention will appear from the following description taken in connection with the drawings, wherein:

10 Figure 1 is a view showing a part of a front elevation of a Linotype or other machine showing the transfer channel, second elevator, elevator transfer slide, and the elevator transfer slide link with attachments thereon for operating the various parts.

15 Figure 2 is a view showing a front elevation of the intermediate channel.

20 Figure 3 shows a cross section through the upper part of the transfer channel, with parts omitted showing the second elevator resting upon the upper surface of the transfer channel.

25 Figure 4 is a similar section showing the dogs for withdrawing the sliding plates that hold the matrices, and with the sections at each side taken at points adapted to show the dogs on the respective sides.

30 Figure 5 is a similar section showing the means for slidably attaching the sliding matrix holding plates to the lower edges of the second elevator.

35 Figure 6 is a plan view looking upward, showing the under surface of the second elevator.

40 Figure 7 is a plan view looking downward upon the upper surface of the transfer channel.

45 Figure 8 is a view looking in the opposite direction to that shown in Figure 2, showing the back of the transfer channel.

50 Figure 9 is an end elevation showing the forward end of the transfer channel with the operating parts mounted thereon, and with the lower part broken away.

55 Figure 10 is a cross section through the upper portion of the rear wall of the transfer channel, showing the sliding stop and sliding elevator plate, both of which extend through the wall of the channel.

60 Figure 11 is a detail showing a latch provided on the elevator transfer slide link for operating the dog that releases the sliding plate on the rear of the second elevator.

65 Figure 12 is a plan view showing a sloping prong mounted on the forward end of the space band lever pawl.

70 Figure 13 is a side elevation of the pawl and prong shown in Figure 12.

75 A group of matrices representing a line of type, with the space bars between the words, are elevated and fed to the intermediate channel in the usual manner, and, as the elevator transfer slide link passes backward across the transfer channel, a projection, extending downward from the elevator transfer slide, releases the mechanism which raises the matrices upward in the transfer channel, and, as the link returns, it releases a sliding plate on the under side of the second elevator which, during this movement, moves downward upon the transfer channel so that the plate moves in under shoulders at the upper ends of the matrices, and, as the link continues to move, it presses the elevating means downward and moves a stop extending into the transfer channel backward to the starting position, the said stop having been moved outward from its position in the channel by the upward movement of the matrix elevating means, and then, as the second elevator moves upward, a sliding plate on the opposite side thereof is released, and this also moves in under shoulders on the opposite sides

of the matrices, the space bars remaining in their normal positions, and being recovered or returned by the space band lever pawl in the usual manner.

These improvements are illustrated in the drawings, in which numeral 1 indicates the transfer channel, numeral 2, the second elevator, and numeral 3, the elevator transfer slide link by which the device is operated.

10 The transfer channel 1 is substantially the same as that used in present machines, except that the back plate 4 is changed, as shown in Figures 8 and 9, with means thereon for readily holding and elevating matrices, and the second elevator is provided with slidable plates on the 15 lower edges for holding the matrices by the shoulders thereof.

15 The matrices are fed to the transfer channel from the first elevator in the usual manner and, as these are supported from their lower ends, as shown in Figure 9, it is immaterial whether or not they are in one or two lines as, as soon as the matrices are elevated above the space bands, all of them will be in the same elevation.

20 The matrices are fed into the machine in the position shown in Figure 9, with their lower ends resting upon a plate 5 at one side and a ledge 6 at the other, and the space bars are supported in the usual manner, with the projections at their upper ends held in the groove 7 and upon the 25 ledge 8 of the respective sides of the transfer channel, and, as the line of matrices and space bands are fed into the said transfer channel, they engage a stop 9 extending into the transfer channel through a slot 10, and mounted upon a rod 11 through a slider 12. This slider moves along the rod 11, with the stop 9 moving through the slot 10 until the entire line is in the transfer channel, and, at this time, the elevator transfer slide link 3 is moved across the transfer channel, 30 and an arm 13 extending downward from the elevator transfer slide 14, which is connected to the link 3, engages a lug 15 on a suspended vertical bar 16 which releases the holding means of the plate 5, and the plate moves upward to the 35 position indicated by the dotted lines 17 in Figure 9, thereby elevating the matrices to the position shown in Figure 3, in which the matrices are indicated by the numeral 18. The bar 16 is pivotedly attached to a horizontal bar 19 which 40 is connected to the plate 5 by pins 20 and 21 extending through slots 22 and 23, and this horizontal bar is moved upward by springs 24 and 25 on pins 26 and 27 extending downward from the bar 19 and slidably held in bearings 28 and 29. 45 This horizontal bar also moves the bar 11 outward, and this motion withdraws the stop 9 with the part 12 in the position shown in dotted lines in Figure 9, and this movement is accomplished by prongs 30 and 31 having bevel surfaces which 50 slide in under the ends of the rod 11. The members 30 and 31 are fixedly attached to the ends of the bar 19 by screws 32 and 33, and the bar 11 is held inward by springs 34 and 35 which bear 55 against the outer surface thereof. The bar is 60 slidably mounted on pins 36 and 37 which extend through holes in the bar and into the plate 4. The slider 12 is returned to the position shown in Figure 8, which is the normal or starting position, by a shoulder 38 on the link 3 which engages the slider while in the outward position, as indicated by the dotted lines in Figure 9, as shown. And, as the link 3 returns, the lower edge thereof slides over an extension 39 of the 65 bar 19, moving the bar downward from the position 70 shown in Figure 9.

75

tion shown in dotted lines in Figure 8 to that shown in full lines, and the bar is held downward by a seat 48 which snaps over a pin 41 extending outward from the plate 4, and it will be noted that, as the arm 13 engages the member 15, it moves the seat 48 away from the pin 41, as indicated by the dotted lines. The bar 16 is resiliently held against the pin 41 by a spring 42 on a rod 43 held in a bearing 44, with the bar 16 slidably in a groove 45 in the head 46 of the pin.

After the matrices have been moved upward by the foregoing mechanism which raises the plate 5, a latch, formed by a plate 47 mounted on the link 3, engages a projection 48 extending outward from the end of a lever 49, resiliently held downward by a spring 50, and raises this end of the lever, causing the dog 51 on the opposite end to move downward releasing a shutter 52 which is moved in under the shoulders at the upper ends of the matrices by springs 53 and 54 on the sides of the second elevator 2. The lever 49 is pivotally mounted on a pin 55 on the side of the upper edge of the back plate 4 of the transfer channel, and the dog 51 is slidably held over a pin 56 through a slot 57. The shutter 52 is slidably mounted on the under side of the back of the second elevator 2 by screws 58 and 59 in slots 60 and 61, with the heads of the screws in slots 62 and 63 extending transversely of the shutter as shown in Figures 5 and 6. As the second elevator moves downward upon the upper surface of the transfer channel to the position shown in Figure 2, an eye 64 at the side of the shutter 52 slides over the dog 51, and the sloping surface of the dog draws the shutter outward against the springs 53 and 54 to the position shown in Figures 3 and 4, and it will be noted that, as soon as the member 47 raises the member 48 and lowers the dog 51, the shutter 52 is free to move inward under the shoulders of the matrices, thereby holding the matrices in the second elevator. The second elevator is also provided with an additional shutter 65 on the opposite side, which is also slidably mounted upon screws 66 and 67 in slots 68 and 69, and this shutter is also provided with eyes 70 and 71 which slide over the bevel surfaces of dogs 72 and 73 rigidly mounted upon the upper edge of the side 74 of the transfer channel 2, and this shutter is resiliently held inward by springs 75 and 76 similar to the springs 53 and 54. This shutter is, therefore, moved outward by the dogs 72 and 73 as the second elevator moves into position upon the upper surface of the transfer channel, and this shutter remains outward until the second elevator starts to move upward, and at this time the shutter 65 moves off of the dogs 72 and 73 and slides inward with the inner edge under the shoulders of the matrices at this side.

The transfer channel 1 is provided with a guide 77 which extends upward and fits into a recess 78 in the second elevator, thereby guiding the second elevator into position, as shown in Figures 1 and 2. The second elevator 2 is mounted upon the arm 79, which is the same as arms used in the present machines, however, it will be understood that the connection between the second elevator and arm may be made as desired.

The member 47 is resiliently mounted with a rocking motion on a block 80 on the link 3 through pins 81 and 82, resiliently held downward by springs 83 and 84, and resting upon a projection 85 on the block. The member 47 extends to one side of the block, and it will be

noted that, as it moves in one direction, the end 86 will slide over the bevel surface 87 of the member 48, whereas, as it moves in the opposite direction, the bevel surface 88 of the member 47 will ride under the member 48 and raise the end of the lever 49 to lower the dog 51.

In Figures 12 and 13, a device is illustrated which is not directly connected to the transfer channel, however, by forming the second elevator in this manner, it has been found necessary to place a prong 89 on the space band lever pawl 90 so that, as the pawl moves forward, the member 89 will engage a bevel surface 91 at the end of the second elevator and permit the pawl to raise upward as the pawl approaches the second elevator, as shown in Figure 2. This device may, however, be formed in any manner, and any means may be used for guiding the pawl into such a position that it will not strike the end of the second elevator but will ride upward as it moves toward the end thereof.

These parts, as shown and described, are incorporated in a Linotype or other similar machine without changing any of the other remaining parts, however, the teeth on the triangular shaped bar in the distributor box may also be eliminated, so that the teeth of the matrices may not be used until the matrices are placed upon the distributor bar in the distributing mechanism. This device, therefore, makes it possible to transfer the matrices from the first elevator to the distributor bar without engaging teeth in the triangular shaped openings therein at any point in this operation.

It will be understood that changes may be made in the construction without departing from the spirit of the invention. One of which changes may be in the use of other means for raising or elevating the matrices in the transfer channel, another may be in the use of other means for gripping the matrices in the second elevator, another may be in the use of other means for transferring the matrices with or without the space bars into and out of the said transfer channel, and still another may be in the use of other means for operating the respective parts.

The construction will be readily understood from the foregoing description. In use the device may be provided as shown and described, and the parts may be installed in a machine as used for Linotype or other similar machines, and the matrices will be elevated upward away from the space bars and gripped and held in the second elevator as shown and described, and, after they have moved upward, the space bars will be recovered or moved backward to their normal positions by the space band lever pawl in the usual manner.

In providing this means for transferring the matrices from the transfer channel to the second elevator, it will be noted that the matrices are positively held in all positions and every movement is absolutely assured. The matrices normally rest upon the members 5 and 6 in the transfer channel 1, and, in order to insure their being absolutely held, the front side 74 of the transfer channel may be provided with a resiliently held plate 92, which may be mounted in a slot 93 and resiliently urged outward by springs 70 and 94. This plate has a tendency to line up the matrices and positively hold them against the opposite side 4 so that they will be assured of being engaged by the plate 5 as this plate moves upward. The plate 92 is positioned directly

above the ledge 6, and it will be understood that the end of the plate will be curved backward similar to the surfaces at the end of the transfer channel as shown in Figure 7, the edge of the plate corresponding with the surface 95 which is also slightly curved to facilitate the transfer of the matrices into the said transfer channel.

As hereinbefore stated, this particular construction makes it possible to eliminate the auxiliary step in which matrices for two different styles of type are transferred into the transfer channel, as the construction of the channel makes it possible to receive matrices at different elevations, and, as soon as they are moved upward, all of the matrices are aligned with the shoulders at their upper ends gripped by the shutters of the second elevator. The second elevator then transfers the matrices to the distributor box where they are held and distributed 20 in the usual manner.

Having thus fully described the invention, what I claim as new, and desire to secure by Letters Patent, is:

1. A second elevator for Linotype and other 25 similar machines having an inverted channel shaped head, with shutters at the lower edges of the sides for holding matrices by shoulders at the upper ends of the sides.

2. A device as described in claim 1, in which 30 the holding means comprises horizontally slid- able plates resiliently held inward and adapted to move outward by engaging bevel surfaces upon a device upon which the said elevator is positioned, and means resiliently holding said plates 35 inward.

3. In combination with a device as described 40 in claim 1, means releasing one of said plates before the elevator is moved upward, and means releasing the other of said plates as the said elevator starts upward.

4. In type making machines of the Linotype 45 type having a transfer channel, a distributor box, a second elevator for transferring matrices from the intermediate channel through the distributor box and an elevator transfer slide link for recovering space bands from the intermediate channel; means in said transfer channel for supporting and elevating matrices from the lower ends thereof, and means in said second elevator 50 for supporting matrices by the shoulders at the outer sides of the upper ends.

5. A device as described in claim 4 having a 55 slidable plate in said intermediate channel, a latch holding said plate downward, and means releasing said latch and plate by the elevator transfer slide link.

6. A device as described in claim 4 having a stop slidably mounted on said transfer channel and means on the elevator transfer slide link for 60 returning said stop after the matrices have been removed from the channel.

7. A device as described in claim 4, character- 65 ized by slidable plates on the under side of the second elevator providing the matrix holding means thereof, and projections having bevel surfaces adapted to move said slidable plates outward providing receiving space for the matrices as the second elevator rests upon the upper surface of the transfer channel.

8. A device as described in claim 4, character- 70 ized by slidable plates on the under side of the second elevator providing the matrix holding means thereof, and projections having bevel surfaces adapted to move said slidable plates outward 75 providing receiving space for the matrices as the

second elevator rests upon the upper surface of the transfer channel, and means releasing one of said side plates by the elevator transfer slide link after matrices are in position with their upper ends in the second elevator.

9. A device as described in claim 4 having a 5 slidable plate on the inner surface of the intermediate channel, resilient means urging said plate upward to elevate matrices in the transfer channel to gripping positions in the second elevator, a latch holding said slidable plate downward, and a projection on the elevator transfer slide link for engaging and releasing said latch.

10. A device as described in claim 4 having a 10 slidable plate on the inner surface of the intermediate channel, resilient means urging said plate upward to elevate matrices in the transfer channel to gripping positions in the second elevator, a latch holding said slidable plate downward, and a projection on the elevator transfer slide link for engaging and releasing said latch. 15

11. In combination with a Linotype or similar 20 machine having a transfer channel, a transfer slide and a second elevator, means transferring a matrix from the transfer channel to the second elevator and supporting it therein without a grooved bar and without engaging the sorting teeth of the matrix, said transferring means 25 comprising rails positioned in the second elevator as the second elevator is positioned upon the transfer channel, and said gripping means on one side of the second elevator adapted to be released to permit it to be moved inward by the said elevator transfer slide link.

12. A device, as described in claim 11, char- 30 acterized in that the matrix is delivered to the second elevator with a vertical movement of the matrix. 35

13. The process of delivering a matrix to the 40 second elevator of a Linotype or other machine with a vertical movement of the matrix, and characterized in that the said vertical movement constitutes the transfer or delivery of said matrix 45 from the transfer channel to the second elevator of the machine.

14. A second elevator for Linotype or other 50 machines having a sliding plate at one side adapted to move under a projection at the side of a matrix positioned therein for supporting said matrix.

15. In a Linotype or other machine having a 55 transfer channel, a transfer slide and a second 60 elevator, means supporting matrices in said transfer channel by the lower ends thereof, means raising the said supporting means to elevate the matrices, means on said supporting means adapted to be engaged by a part of the transfer slide 65 for moving said supporting means downward as the slide moves across the machine, and means releasing said movable supporting means as the said transfer slide moves backward.

16. A device, as described in claim 15, having 70 a follower positioned in the path of matrices moved into said transfer channel adapted to hold a line of matrices together, means moving said follower out of the path of the matrices as the said movable supporting means is moved down- 75

17. In combination with a device as described in claim 15, means on the second elevator for supporting the matrices therein by passing inward under the shoulders of the matrices as the second elevator starts upward.

18. In combination with a device as described in claim 15, means on the second elevator for supporting the matrices therein by passing inward under the shoulders of the matrices as the second elevator starts upward, said transfer channel having means opening said holding ward, and means returning said follower to the original position.

means as the second elevator arrives in position upon the upper end of said transfer channel.

19. In Linotype or similar machines having a transfer channel and a second elevator, means supporting matrices in the said transfer channel, and means moving the said supporting means vertically upward, moving the upper ends of the said matrices into the said second elevator.

DAVID DIAMOND.
